STRUCTURAL SECTION

John J. Senglari, Los Angeles, Calif.

Application May 31, 1947, Serial No. 751,565

3 Claims. (Cl. 72—16)

1

This invention relates to building construction and has for its principal object to provide structural building members and assemblies which are economical, strong and easy to fabricate and assemble.

It has, heretofore, been proposed to provide prefabricated structural members, such as walls, floors, roofs, struts, etc., or parts thereof which are adapted to be assembled to form buildings and similar constructions of desired sizes and shapes. Such a building method has the advantage of reduced costs through benefit of mass production of the structural members and the additional advantage of rapidity of assembly of the building. Such prefabrication techniques are presently limited, however, in their acceptance by an inherent inflexibility of design, flimsy construction, disproportionate costs or a combination of these factors.

The present invention therefore, has as an object the provision of a sectionalized building unit and auxiliary equipment which is relatively inexpensive to manufacture, simple to assemble and adaptable to the construction of sturdy buildings of substantially any design.

The above contemplated object is accomplished in the present invention by the provision of a basic unit or wall segment joinable directly to a pre-poured foundation together with modified segments for forming corners, door jambs, window sills and the like. Each of these segments in the preferred embodiment of the invention comprises a metal framework substantially encased with concrete and filled with suitable insulating material. Means are provided which may form a part of the framework of the segment itself for linking these various sections to each other in any desired combination. By these means the building of substantially any desired size or shape may be constructed with the wall units of the invention. The units or segments are adapted to be affixed to conventional foundations by means as hereinafter set forth and to support any desired type of roofing structure so as to be suitable in any style of construction.

The foregoing and other features of my invention will be better understood from the following detailed description and the accompanying drawings of which:

Fig. 1 is a partial elevation view of a wall constructed from the units of the invention;

Fig. 1a is a cross section view taken at line 1a—1a of Fig. 1, showing details of construction of insulation bats in concrete;

Fig. 2 is a plan view on the line 2—2 of Fig. 1;

2

Fig. 3 is an enlarged plan view of the section 3—3 of Fig. 2;

Fig. 4 is an enlarged plan view of the section 4—4 of Fig. 2;

Fig. 5 is an enlarged plan view of the section 5—5 of Fig. 2;

Fig. 6 is a plan view of that portion shown in Fig. 4 illustrating various modifications thereof;

Fig. 7 is an enlarged plan view, partially in section, of the section 7—7 of Fig. 2;

Fig. 8 is a sectional elevation on the line 8—8 of Fig. 1;

Fig. 9 is a sectional plan view on the line 9—9 of Fig. 1;

Fig. 10 is an enlarged view of the hinge mount shown in Fig. 9;

Fig. 11 is an end elevation partly in section of one of the assembled units of the invention;

Fig. 12 is a sectional elevation on the line 12—12 of Fig. 11;

Fig. 13 is a sectional elevation on the line 13—13 of Fig. 11;

Fig. 14 is an elevation view of a section of the spline used to link the units to each other;

Fig. 15 is a section plan view of the spline taken on the line 15—15 of Fig. 14;

Fig. 16 is an isometric view of the internal framework of the wall segment of the invention.

Fig. 17 is an enlarged plan view of one of the spline plates shown on the framework of Fig. 16;

Fig. 18 is a side elevation of the spline plate of Fig. 17;

Fig. 19 is a side elevation of one of the strut members shown in the framework of Fig. 16;

Fig. 20 is a plan view of the mold member which I may employ to form the segments;

Fig. 21 is a sectional elevation on the line 21—21 of Fig. 20;

Fig. 22 is a detailed view of the key 224 of Fig. 21;

Fig. 23 is a detailed view of the wedge 226 of Fig. 21;

Fig. 24 is a section taken on the line 24—24 of Fig. 1;

Fig. 25 is a section taken on the line 25—25 of Fig. 1; and

Fig. 26 is a sectional plan view of the means of linking a partition to an outside wall.

The structural wall members as shown in Fig. 1 include the plain section 10, the window section 11 and the door section 12, each of which are hereinafter described. In the wall section of Fig. 1, the plain section, the window section and the door section are joined to each other as being illustrative of such a combination, however, the

sections may be affixed in any desired combination and there may be any number of repetitions of the same section in a given wall. At the left hand end of the plain or blank section 10 there is shown a section 14 projecting at right angles from the section 10 forming a corner in the wall 16.

These units comprise a metal framework as for example, the type shown in Fig. 16, hereinafter described, in which is encased suitable insulating material such as a plurality of insulating bats, two of which are identified as 18 and 19, and are shown in the cutaway portion of Fig. 1. Completing the framework, with the exceptions hereinafter noted, is a layer of concrete which, in the embodiment described, forms a covering for the framework and for the insulating bats and a filling between the bats. Thus in the cutaway portion of Fig. 1 it is seen that the concrete 20 surrounds the insulating bats 18 and 19. This type of construction is evidenced from the sectional elevation of the member 14 in Fig. 1 wherein there is seen three separating insulating bats 22, 23 and 24 encased in the concrete 26 in which is imbedded the longitudinal members 27, 28, 29, etc., of the metal framework.

The details of construction and assembly as set forth in Figs. 2 through 15 may be more clearly understood after the description of the framework and skeleton of one of the wall segments as shown in Figs. 16 through 19.

Fig. 16 is an isometric view of the structural skeleton of a blank segment such as the segment 10. The framework consists of the four metallic U-bars 32, 33, 34 and 35 tied together in equally spaced relationship by the longitudinal stays, or rods, 37, 38, 39, 40, etc. These U-bars comprise the two parallel vertical legs, as shown, joined at the top by the base of the U. The term "bar member" as used herein denotes the structural member having these two legs, and the term "U-bar" refers to the bar member with the two legs joined by the base of the U. The stays are affixed to the intermediate U-bars 33 and 34 by the struts 42, 43, 44, 45, etc., which clamp to the stays and which are grooved to ride in the longitudinal U-bars. The stays 37, 38, 39, 40, etc., are anchored at one end of the section by the spline plates 48, 49, 50 and 51 and at the other end by similar spline plates as shown, and thus serve to space the U-bars 32, 33, 34, 35, at equal distances along the horizontal, longitudinal axis of the skeleton.

The spline plates 48, 49, etc., are of importance in furnishing the means whereby the individual wall units are interlocked with each other. Such a spline plate is shown in an enlarged plan view in Fig. 17 and in side elevation in Fig. 18. The plate such as the plate 48 is provided with the opposite slots 54 and 55 which fit on the two legs of one of the U-bars such as the U-bar 32, and the slots 56 and 57 which provide means for anchoring the stays such as the stays 37 and 38. The plate 48 is also provided with the keyway 60 which is adapted to engage means as hereinafter described for interlocking two sections to each other. In the side elevation of Fig. 18 wherein the slots 55 and 57 may be seen, the rear tabs 62 and 63 are shown to be bent downward at right angles from the main body of the plate. These tabs 62 and 63 serve as cleats to anchor the spline plate in the cement in the manner hereinafter described.

The struts 42, 43, 44, etc., like the spline plates,

may be punched by mass production techniques from sheet metal. A strut, such as the strut 42, is shown in side elevation in Fig. 19. The struts, like the spline plates are provided with end grooves 64 and 65 to engage the two legs of the U-bars such as the U-bar 33. The strut is further provided with the two longitudinally disposed slots 66 and 67 formed by punching the tabs 68 and 69 from the strut along the longitudinal axis thereof. Tabs 68 and 69 are then employed to clamp around the longitudinal stays 37 and 38.

The slots in the struts and spline plates which accommodate the stays and the U-bars are conveniently punched so as to retain projecting ears which are bent out of the way in the punching operation as shown for example on the spline plate 49 of Fig. 16. After assembly of the skeleton these ears are peoned around the stay or U-bar as shown in Figs. 2, 3 and 4 to provide additional strength. Although these ears are a desirable feature they are not a necessary element of the invention.

To fabricate a wall section the skeleton such as shown in Fig. 16 is placed in a mold such as the mold shown in Figs. 20 and 21 and as hereinafter described, so that side faces of the skeleton will be on a horizontal plane. A layer of concrete is then introduced into the mold so as to partially immerse one side of the skeleton and a plurality of insulating bats are placed in each of the rectangular sections formed by the stays and the U-bars of the skeleton. Additional cement is then added to complete the encasement of the skeleton and to fill the spaces between the insulation with the cement. Means are provided in the fabricating process to prevent the cement, when added, from filling the key-ways in the spline plates so that these key-ways may be used to join the individual sections to each other in the manner hereinafter described.

In Fig. 2, which is a plan view on the line 2-2 of Fig. 1, means of joining two segments to each other in axial relationship as well as in right angle relationship are shown. The unit 10 is provided as shown in Fig. 16, with a plurality of spline plates such as the spline plate 48 and the spline plate 70 projecting in the horizontal plane from the vertical end of the segments. The segment 11 is joined to the segment 10 as shown in Fig. 2 and in the enlarged plan view of Fig. 4 by means of the spline 72 projecting through the key ways provided in the spline plate 70 of the segment 10 and the spline plate 74 of the segment 11 and through similar key-ways in each of the spline plates projecting from the end faces of the segments 10 and 11. (In the manner shown in Fig. 16.) An important feature of the invention resides in the manner of joining the individual units together without requiring the use of bolts, welding, wiring or other expensive and time consuming means.

To form a corner as shown in Fig. 2 a corner section is provided which comprises the three vertical rods 76, 77 and 78 upon which are mounted a plurality of spline plates such as the plate 80 which are of somewhat different configuration than the spline plates forming a part of the flat sections. The skeleton framework of the corner member 82 is encased in concrete in a suitable mold. The spline plate such as the plate 80 is provided with a pair of key-ways 84 and 85 as more clearly shown in Fig. 3. Thus,

the wall segment 10 may be joined at right angles to a segment 26 by means of the corner segment 82 by the use of the splines 88 and 89 joining the spline plates of the corner segment 82 to the spline plates of the segments 10 and 86.

In Fig. 5 there is shown in detail a plan view of a portion of the wall segment 10 as is shown in Fig. 2. In Fig. 5 there can be seen the longitudinal stays 37 and 38 and the legs 33a and 33b of the U-bar 33 as shown in Fig. 14. The strut 42 affixed to the legs 33a and 33b clamps the longitudinal stays 37 and 38 to the U-bar 33 by means of the tabs 68 and 69 which are adapted to be crimped over the stays 37 and 38 in the manner shown in Fig. 16. To illustrate the placement of the insulating bats in relation to the framework and the concrete facing, two of such bats are shown in dotted lines and are indicated as the bats 90 and 91.

Fig. 6 is a plan view of the juncture of two wall segments similar to that shown in Fig. 4, but including additional features which may be employed. Thus, as shown in Fig. 4 when two of these segments are interlocked to each other by means of a spline such as the spline 72 passing through the key-ways in the spline plates 70 and 74 and the companion plates disposed along the vertical ends of the segments 10 and 11 a small space separates the concrete surfaces thereof from each other. In Fig. 4 this space was shown to be filled with mortar or the like inserted after assembly of the segments 10 and 11 so as to exhibit a smooth walled surface. An additional means of closing this space is by the use of a molding shown in sectional plan view in Fig. 6 as the molding 94 which is a continuous strip provided with a plurality of clips such as the clip 96 which is adapted to be inserted in the space to hold the molding 94 against the surfaces of the segments 10 and 11. The clip 94 comprises the body member 96a which is adapted to clip into the semi-circular indentations formed in the concrete in the processes of molding as hereinafter described. Such semi-circular indentations are shown in Fig. 6 at the opposite side of the segments from the molding 94 and are identified as 98 and 99. These indentations serve not only as a means of holding a molding such as the molding 94 but also as a key-way for the mortar between the sections. Alternatively if it is desired to erect a structure which may be readily taken down the mortar between the sections is omitted and the semi-circular indentations may be used for holding a caulking cord.

In Fig. 7 there is shown a partially cut away plan view of the section 7-7 of Fig. 2 illustrating the detail of the wiring conduit 100 provided in each of the wall segments. In Fig. 7 there is again shown the longitudinal stays 37 and 38, the cement casing 20 and, in the cutaway portion, the insulating bat 90. In forming the wall segment 10 in the manner hereinafter described the insulating bat 90 and the corresponding insulating bats lying in vertical relationship to the bat 90 are provided with a wiring chase 102 which is, at the time of molding, covered by a sheet 103 to prevent the migration of concrete into the chase 102. Connected between the wiring chases in each of the bats such as the bat 90 there is provided a small conduit section such as the section 105 shown in Fig. 7 which acts as a communication through the concrete, which fills the spaces between the bats, between the successive wiring chases in each of the insulat-

ing bats. There is thus provided from the top to the bottom of the wall segments a wiring conduit 100 formed from the wiring chases in each of the insulating bats and vertically disposed in relation to each other and pipe segments communicating between the wiring chases in each of the bats. As shown in Fig. 6 the pipe segment 106 which would be the next successive pipe segment to the segment 105 as shown in Fig. 7 is flattened on one face so as to pass the stay 38. In the same manner the pipe segment 105 will be flattened on one face to pass by the stay 40 which lies directly beneath the stay 38 as shown in Fig. 14. The pipe segment 105 is shown in the partially cut-away elevation view of Fig. 11. In the preferred form as shown in Fig. 11 the pipe segment extends into the chases in the adjoining insulating bats to aid in attaining proper alignment and is notched at 107 to fit around the stay 38 rather than flattened as was shown in respect to the segment 106 (Fig. 6). Either means of avoiding the stay may be employed.

The structure of the wall unit 12 which includes the doorway is shown in greater detail in Figs. 8, 9 and 10. Fig. 8 is a sectional elevation taken on the line 8-8 of Fig. 1; Fig. 9 is a sectional plan view taken on the line 9-9 of Fig. 1 and Fig. 10 is a section taken on the line 10-10 of Fig. 9. In Fig. 8, the wall segment 12 is shown supported on the foundation 108. The means of anchoring this and the other wall segments to the foundation is described with relation to Figs. 11 and 13. As shown in Fig. 1 the wall segment 12 is shaped so as to accommodate a door which may be hinged thereto in any conventional manner by construction of a door frame in association with the wall section.

In a preferred form of the invention the opening provided in the wall section 12 is shaped in the form of a door frame and conventional door stops are mounted by affixing the same to metal plates which are imbedded in the concrete of the wall section itself and which are tapped to permit the reception of screws therein. Thus in Fig. 8, the door stop 110 is mounted directly to the inside edges of the wall section 12 as shown at 111. The door 113 is hinged to the wall edge in a similar manner, i. e. the hinge is affixed directly to a tapped plate imbedded in the concrete of the wall segment 12. This construction is apparent from Fig. 9 which is a sectional plan view on the line 9-9 of Fig. 1.

In Fig. 9 the construction of the wall segment 12 is shown including the longitudinal stays 120 and 121 anchored to the spline plates 122 and 123 and the longitudinal stays 124 and 125 extending from the spline plate 126 to the next spline plate or to a strut as shown in Fig. 14.

The door stops 110 are screwed to the inner edges of the wall 12 by means of the screws 130 and 131 for example, projecting into the plates 132 and 133 which are formed by bending a flat piece of metal in a U shape and bending the tips of the legs of the U toward each other so as to provide means for anchoring the plate in concrete.

In a similar manner the plate 136 is anchored in the concrete and provides means for affixing the hinge 138 to the inside edge of the wall segment 12 and thus to mount the door 113 to the wall. The construction of one form of plate which may be employed as the anchoring means is shown in Fig. 10 which is a section on the line 10-10 of Fig. 9. As seen in Fig. 10 the inner leaf 138a of the hinge 138 formed from

the inner leaf 138a and the outer leaf 138b is affixed to the plate 136 by the bolts 139, 140 and 141. The outer leaf 138b is affixed to the door. The plate 136 is conveniently a channel member with the inner extremities of the legs 136a and 136b bent inwardly as shown so as to anchor the member 136 in the concrete of the wall segment 12. Also shown in Fig. 10 in dotted lines is the construction of the plate 133 to which the nut 131 affixes a portion of the door stop 110. This anchoring means is similar to the member 136 as seen.

Also shown in Fig. 9 is a sectional view of the conduit 150, similar to the conduit shown in Figs. 6 and 7 illustrating the means whereby a switch box may be easily incorporated at any desired place in the wall segment. Thus when the conduit 150 is installed during the fabrication of the wall segment 12 a plug 152 of insulation may be injected at any desired location so as to prevent the filling of that particular volume with concrete. In this manner at any time thereafter the thin wall of concrete between the outer edges of the plug 152 and the surface of the wall section may be tapped and the insulating plug removed. A switch box may be inserted therefor making connection with the wires traveling through the conduit 150.

The entire construction of a wall section together with the means for joining such a section to a second section, the means of anchoring the segment to the concrete and the means of finishing off the top of the wall so as to be adapted to construct a roof thereon, are shown in Figs. 11, 12 and 13. The wall section shown in Figs. 11, 12 and 13 is assumed to be, for convenience in description and cross-reference, the segment 10 as shown in Fig. 1 and in Fig. 16 in skeleton.

Fig. 11 is a sectional elevation partially in section of the vertical end face of the wall segment 10 broken at two points to show the various features of construction thereof. Thus the upper portion is shown in the absence of the concrete casing, the middle section is shown as it would appear with the concrete casing complete and is cutaway in part to show the internal construction thereof, and the lower section is shown without the concrete casing so as to more clearly illustrate the means of anchoring the same to the foundation 108. The end U-bar 32 (see Fig. 16) is shown in solid lines in the upper and lower portions of Fig. 11 and in dotted lines in the central portion. Also in Fig. 11 there is seen the spline plate 48 and the spline plate 51 (Fig. 16), and the ends of the longitudinal stays 37 and 38 as well as the corresponding stays tying into the spline plate 51. As above described with reference to Figs. 2, 3 and 4, the spline 72 engages in the key-ways provided in the spline plates 48, etc., and furnishes the means for locking the wall segment 10 to a second wall segment such as the segment 11 (Fig. 1).

The means of anchoring the wall segments to the foundation 108 is shown in end elevation in Fig. 11 and in side elevation in Fig. 13. When the concrete is poured, a plurality of anchor plates, such as the anchor plate 160, are mounted therein at evenly spaced intervals to engage the splines such as the spline 72 which joins two wall sections to each other. The anchor plate 160 is conveniently a flat plate as shown in Fig. 13 bent at right angles at its lower end so as to be firmly locked to the foundation 108 and projecting above the foundation a distance sufficient

to permit engagement with the spline 72. In the portion of the anchor plate 160 projecting above the foundation 108 there is provided the transverse hole 162. Similarly, in the bottom extremity of the spline 72 is a corresponding transverse hole 164. A key 165 is provided which comprises a U-shaped member, the legs of which are adapted to project through the holes 162 and 164 in the anchor plate 160 and the spline 72, respectively. In this manner the individual sections are anchored to the foundation without the necessity of bolting or welding them thereto. I have found that this boltless assembly and anchoring of the individual sections greatly expedites the construction work.

In fabricating the segment 10 the lower edge thereof is formed in the nature of a flat surface with the exception of a semi-circular groove running along the central axis of the lower edge. This semi-circular groove 167 provides a moisture seal by permitting the infiltration of the water proof cement 168 laid down just prior to the placement of the segment 10 on the foundation 108.

No means are required for locking the key 165 into the holes provided therefor in the anchor plate 160 and the spline 72 inasmuch as the weight of the wall segment will hold the same in place and both longitudinal and vertical motion will be prevented by the key 165. Further, after joinder to the wall section 10 of a second section such as the section 11, the space separating the two may be filled with mortar or the like which will have the effect of locking the key 165 in position.

The top finishing of the wall section 10 is shown in the upper portion of Fig. 11 and in the side view of Fig. 12. As shown in Fig. 12, the spline 72 is provided with a transverse hole 170 which provides means of locking the spline in position. To so lock the spline in position the spanner 172 and a similar spanner 173 are engaged with the spline and are held in position by the wedges 174 and 175 inserted through the hole 170 in the spline 72.

A conventional expanded eye beam is disposed along the top of the U-bars such as the U-bar 32 and a stud 182 is laid along the top of the eye beam 180 and anchored down by the bolts 184, 185, etc., which are bent at their lower extremities to engage the top member of the U-bars 32, 181, etc. The roofing structure, of any desired type, may be anchored directly to the stud 182. A molding 174 is shown in Fig. 11 to indicate the relationship of the finishing assembly to an imaginary ceiling 176.

The spline member 72, hereinbefore described, is shown in detail in the elevation view of Fig. 14 and the sectional plan view of Fig. 15. The spline, as shown in these figures comprises two metal strips 72a and 72b joined to each other at a number of bosses such as the bosses 188 and 189 spaced along the longitudinal axis of each strip by spot welding or the like. The strips are flared outwardly at their outer edges so as to be locked in the key-ways provided in the spline plates when inserted therein in the manner described.

The wall segments of the invention may be conveniently formed in a mold such as that shown in Figs. 20 and 21. Fig. 20 is a plan view of the mold and Fig. 21 is a sectional elevation on the line 21—21 of Fig. 20. The mold comprises a supporting framework which consists of the interlaced expanded eye beams 190, 191, 192,

193, 194 and 195. These expanded eye beams are of the type shown in Fig. 21, as the eye beam 191. It may be here noted that the expanded eye beams are similar to the expanded eye beam 180 shown in Fig. 11. In order to interlace the longitudinal eye beams 193, 194 and 195 with the transverse beams 190, 191 and 192, I have found that one or the other is conveniently broken and welded in the manner shown in Fig. 21. Forming the mold itself are the angle irons 198, 199, 200 and 201 which rest on the framework formed by the interlaced eye beams as shown in Fig. 20. Mounted on the extremities of each of the eye beams are the stops 204, 205, 206, etc., and disposed between the outer edge of the horizontal portion of the angle iron and the stops 204, 205, etc., are the wedge pairs 208, 209, 210, etc. This relationship is most clearly seen in Fig. 21 wherein the wedges 209a and 209b are disposed between the outer edge of the horizontal portion of the angle iron 200 and the stop 205 welded directly to the eye beam 191.

Each of the angle irons have welded to their bottom horizontal surface a plurality of cleats 212, 213, 214, etc. The relationship of the cleat to the angle irons is shown most clearly in the elevation view of Fig. 21, wherein the cleat 213 is shown welded to the bottom horizontal surface of the angle iron 200. The purpose of these cleats is to support the bottom 216 of the mold 12. This bottom 216 may be of plywood, metal or any other structural material and serves to form one face of the unit being molded.

The unit skeleton such as shown in Fig. 16 is laid horizontally in a receptacle formed by the four angle irons and the bottom member 216 and is held therein by engagement of the key-ways of the spline plates such as the spline plates 218 shown in Fig. 21. To prevent the filling of the key-ways of the spline plates with concrete and to form a continuous channel between successive key-ways, the continuous strips 220 and 221, together conforming to the outline of the key-ways are disposed therein and locked in position by the U-shaped wedge 226. The strip members 220 and 221, which positioned as shown in Fig. 21 form a continuous channel through the key-way and between each of the spline plates on a given end of a wall segment are under a spring tension, and the key 224 when in engagement therewith will cause the same to assume the position shown in Fig. 21. However, by reference to Fig. 22 which is a detailed view of the key or locking means 224, it is apparent that when the key 224 is turned to the position shown in Fig. 22, i. e. so that the engaging tip 225 has its narrowest surface in the plane of the longitudinal axes of the members 220 and 221, the spring tension will not be exerted thereon and they may be collapsed and withdrawn from the channel formed thereby.

To maintain the key 224 in the engaged position shown in Fig. 21 during the pouring operation, the U-shaped wedge 226, shown in Fig. 23 is inserted between the vertical outside face of the angle iron 200 and the collar 224a of the key so as to exert a sufficient tension to prevent the shifting of the key 224.

As described with relation to Fig. 6, the end edges of the wall section are provided with parallel grooves 98 and 98a which are formed therein by the rods 99 and 99a mounted to the angle iron 200 and similar rods mounted to the member 201.

In forming the wall section, the framework as shown in Fig. 16 is laid within the rectangular bed formed by the mold as shown in Figs. 20 and

10
21 and engaged therein as above described by means of the key-ways in the spline plates of the framework. A layer of concrete is then poured into the mold sufficient to cover the lower portions of the framework as it lies horizontally within the mold. A layer of insulation is then added conveniently in the form of individual bats which may be placed in the sections formed by the framework. The mold is then filled with concrete to within approximately one-half inch of the top. In this filling process the concrete will infiltrate between the plurality of insulating bats which have been added and will form a concrete skeleton separating the bats from each other. In a preferred embodiment of the invention the outside face of the section is finished with a one-half inch coating of waterproof cement so as to give a finished appearance thereto.

If electrical wiring conduits are to be provided in a particular section they will be formed in the manner as shown in Fig. 7 and described in relation thereto. Thus, the bats employed will have wiring chases formed therein which will be covered so as to prevent infiltration of concrete and which will be joined by means of conduits or pipes embedded in the concrete separating one bat from the other. When the unit is ready to take out of the mold the wedges such as the wedge 226 is removed from the key such as the key 224 which by turning through a 90° angle releases the strips 220 and 221 forming a channel through the key-ways of the spline plates and these strips may be conveniently removed after the angle iron forming the vertical side of the mold are retracted from the wall segment. These angle irons are thus retracted by removing the wedges lying between the angle irons and the stop members affixed to the extremities of the eye beams forming the base of the mold. Thus in Fig. 21, the angle iron 226 may be retracted from the wall segment formed in the mold by removing the wedges 209a and 209b which hold the angle iron in position between the stop 205 and the angle iron.

45 In Fig. 24 which is a section on the line 24—24 of Fig. 1 and Fig. 25 which is a section on the line 25—25 of Fig. 1, the means of framing a window in a section such as the section 11 (Fig. 1) is shown. As shown in Fig. 24 a channel member 230 is cast into the wall unit adjacent the sides of the window opening and is tapped at spaced intervals to receive a screw such as the screw 232 affixing the window frame to the sides and top of the window opening. The channel member 230 may run the entire length of the window opening or there may be provided a number of separate channel members appropriately spaced from each other.

50 55 60 65 70 75 The window sill 234 as shown in Fig. 25 consists of a precast concrete member square cut on its under surface to cleat over the bottom edge 11a of the window opening in the wall section 11 and tapered on its upper face to provide for water run off in the manner of a conventional sill. In the embodiment here shown the sill 234 is provided with the longitudinal channel which coincides with a similar channel 237 in the edge 11a of the window opening. In mounting the sill the metal strip 238 is inserted in the channel 237 and a layer of mortar is spread on the surface of the edge 11a filling the channel 237. Upon placing the sill 234 in the position shown the mortar is forced into the channel 236 and upon hardening retains the sill in position. A longitudinal groove 240 is provided in the lower edge 234a of the pro-

11

jecting portion of the sill 234. This groove 240 serves as a dripper for the water running off the upper face of the sill, preventing its adherence to the face 234a and ultimate migration to the wall 11.

It is to be understood that the invention is not limited to the use of window framing means as above described with relation to Figs. 24 and 25.

Although the description has been so far limited to the assembly of the wall units of the invention as exterior walls it is equally advantageous to employ these units for interior walls and partitions. Such assembly is readily accomplished by use of a modified spline in the manner shown in Fig. 26.

In Fig. 26 a partition 242 is joined to the wall formed by the units 243 and 244 by means of the spline 246. The spline 246 is T shaped in cross section; the head of the T being identical to the spline 72 (Fig. 14) and having welded thereto a leg 247. The leg 247 is formed from two metal strips affixed to each other at a plurality of bosses such as the bosses 250 and 251 and flared at their outer end to lock in the key-way formed in the unit 242 as hereinbefore described. The spaces between the units are conveniently filled with plaster after assembly. It is apparent that another unit could be affixed to the units 243 and 244 opposite the unit 242 by using a spline which was in the shape of a cross; i. e. a spline similar to spline 246 (Fig. 26) with an additional leg projecting therefrom opposite the leg 247.

It is apparent from the foregoing description that I have provided simple, inexpensive and sturdy building units which may be easily fabricated and assembled without the use of bolts; welding or the like and which are adaptable to substantially any design or foundation configuration. The wall segments may be substantially of any dimensions depending upon the size of the building in which they are to be employed. I have found that units four feet wide and eight feet high are convenient for use in most types of building and particularly in dwelling houses where an eight foot ceiling is conventional. However it is apparent that larger or smaller units may be formed for particular purposes. Units as small as 6 inches in height may be desirable for some users whereas units of 20 or more feet in height may find particular application in large buildings. Similarly the width of the units may vary between wide limits say a few inches to 10' or more.

Further, I have provided units of different types whereby plain walls, walls with doors, walls with windows, and combinations of these may be constructed at will. These various types of units are joined to each other by simply inserting a spline, as described, in the key-ways provided in the spline plates at the ends of the individual sections. The means of joinder of one section to another is the same irrespective of what combination of the three types of sections may be employed. This uniformity of means of assembly constitutes one of the features of the invention. Further, means are provided in the nature of a corner member for joining a pair of any of the above types of units together at the corner of the building, and juncture members are provided for fastening partitions and the like intermediate the ends of any wall.

In construction of a building with the structural units of the present invention any desired design may be followed. The foundation is layed

12

with the idea of employing these units and anchoring plates as described are appropriately spaced along the foundation so as to fall between successive units and to be engageable with the splines joining the units. After the foundation is laid the appropriate ones of these three types of units are mounted thereon in the manner described and are joined to each other as shown. In this respect the loop in the U-bars forming a part of the skeleton of each section are conveniently used to grapple the section thus facilitating elevating and positioning thereof. Flooring is laid and the facing of the walls formed by the units of the invention is finished in the manner described. Any desired type of roof may be affixed to the top edges of the wall sections after the edge has been finished as for example in the manner shown in Figs. 11 and 12.

The interior of the structure may be finished in any desired manner by painting, papering, plastering, panelling or the like or the units themselves may be separated by molding as shown in Fig. 6 so as to give the effect of panelling. Similarly the exterior may be finished in any desired manner, but for substantially all purposes a simple coat of paint over the cement exterior of the building units should be sufficient. For purposes of dwellings it may be desirable to stucco the outside or to employ stucco paint to give the effect of a stucco exterior. Further, if desired, certain portions or all of the outside may be covered with wood sheeting to vary the appearance of the house or building.

Although, as previously mentioned the sections can be made any desired size, it may be convenient to facilitate handling, to join two or more units to each other in vertical relationship. Such union can be readily accomplished by finishing the top edge of the bottom and intermediate units so that a flat surface will be exposed and join the units together by a single spline of sufficient length to reach from the foundation to the uppermost unit.

Many modifications will occur to those skilled in the building art without departing from the scope of the invention as set forth in the foregoing description and in the following claims.

I claim:

1. A structural section comprising a skeleton encased in concrete, said skeleton having a plurality of bar members, each bar member comprising a pair of parallel spaced legs lying in a transverse plane across the section, the successive bar members being spaced from each other in a direction perpendicular to the planes of the legs, pairs of parallel spaced stay rods, the respective rods of each pair crossing adjacent respective legs of said bar members and lying in a plane which crosses the planes of the legs, spacing struts extending transversely across the legs of the bar members and the rods of the pairs of rods at the positions where the rods cross the legs, means attaching the struts to the legs and rods at said positions, and each pair of legs and each pair of rods being encased in a continuous mass of concrete, and a plurality of spline plates embedded in the concrete, each of said spline plates being located substantially in the plane of a pair of the parallel stay rods and extending substantially to an edge of the section, each spline plate having a pair of slots extending inwardly from opposite sides thereof, with the respective legs of the bar member nearest said edge passing through said slots and an additional pair of parallel slots extending inwardly from

the protruding edge of the plate in a direction substantially perpendicular to the direction of extent of the first-mentioned pair of slots, and substantially aligned with the inner ends of the first-mentioned pair of slots, the respective rods of the pair of parallel stay rods in whose plane the plate lies, passing through the last-mentioned pair of slots and thereby being anchored therein, and a key-way formed centrally in the edge of the spline plate at the edge of the section, adapted to receive a key for attaching the spline plate to another member.

2. A section according to claim 1 in which the spline plates are provided with tab means projecting at an angle from the edge of the spline plate which is embedded in the concrete for anchor purposes.

3. A skeleton for a structural section, said skeleton comprising a plurality of bar members, each bar member comprising a pair of parallel spaced legs lying in a transverse plane across the section, the successive bar members being spaced from each other in a direction perpendicular to the planes of the legs, pairs of parallel spaced stay rods, the respective rods of each pair crossing adjacent respective legs of said bar members and lying in a plane which crosses the planes of the legs, spacing struts extending transversely across the legs of the bar members and the rods of the pairs of rods at the positions where the rods cross the legs, means attaching the struts to the legs and rods at said positions, and a plurality of spline plates, each of said spline plates being located substantially in the plane of a pair of the parallel stay rods and extending substantially to an edge of the section, each spline plate
